SPEAKER SYSTEM FOR FIRE ALARMS

Gregory J. Schwall and James E. McCarty,
Stockton, Calif.

Application March 18, 1937, Serial No. 131,657

17 Claims. (Cl. 179—5)

This invention relates to fire alarm systems and particularly to a system for use in cities or other communities having a central alarm receiving station and a number of separate engine houses scattered about the city.

At present there are two methods in use for putting in alarms, the street corner boxes and the ordinary telephone. Any box circuit extends through the central station to all the engine houses. A telephone call, however, is received only by the operator on duty in the central station and a message as to the location, character of the fire, etc., had to be ascertained by said operator from the person on the telephone and then transmitted by the operator to the engine houses. Considerable time was sometimes thus unavoidably consumed before the necessary engine company started for the scene of the fire.

It is with the telephone method of giving alarms that our invention deals, and our principal object is to provide a system by means of which, when a person telephones in an alarm, such telephonic conversation is transmitted to and heard in amplified tones simultaneously in all the engine houses as well as in the central station where the message is initially received. In this manner, details and information as to the fire given by the person putting in the alarm, in response, if necessary, to queries by the central station operator, are immediately heard by those on duty in the various engine houses and the firemen can instantly leave for the scene, with information of value for the prompt fighting of the fire when they arrive.

Another object of our invention is to provide a system for the purpose which makes use of the circuit already provided in connection with alarm circuits, without interfering in any way with the operation of the latter. In this manner, but little additional wiring, and no extra cables are needed in adding our equipment to a system already installed and the cost of the additional installation is thus kept down to a minimum.

As usual in connection with the telephoning in of an alarm to the central station, the tape register and other equipment which make some distracting noises are automatically actuated. In connection with the operation of our system therefore it is also an object of our invention to temporarily discontinue the operation of the register, etc., and consequently stop any distracting noises made thereby, while a telephone alarm is being received and transmitted to the various engine houses. There is therefore

nothing to prevent the central station operator receiving the call from properly catching all that is said over the telephone, and likewise those hearing the message in the engine houses will not have their attention distracted from the message being given them.

A further object of the invention is to produce a simple and inexpensive device and yet one which will be exceedingly effective for the purpose for which it is designed.

These objects we accomplish by means of such structure and relative arrangement of parts as will fully appear by a perusal of the following specification and claims.

The figure on the drawing is a diagram of a fire alarm system, showing only those features of a standard alarm circuit necessary to our invention.

Referring now more particularly to the characters of reference on the drawing, the main alarm circuit, which is always closed as required by the fire underwriters, leads into the central station C and thence to the various engine houses H, the alarm sounding devices in the various engine houses being all in series in the circuit. Said circuit comprises an incoming wire 1 leading into the station C and having electrically actuated alarm and recording devices such as a gong G and a register R interposed in series in the circuit. Said wire beyond the devices leads to one terminal of a normally closed relay switch S which includes a movable blade 2. From this blade another wire 3 extends thence to an engine house H where a loud speaker 4, as well as another register R and gong G are interposed in series therein. A condenser 5 of suitable capacity is interposed in an auxiliary wire 3a which is connected to the wire 3 at points ahead of and beyond the register and gong as shown, and thus by-passes the same.

From said engine house the circuit continues to and through the other engine houses, being initially in the form of a wire 6 connected to the wire 3. Interposed in the circuit in each of these other engine houses is a loud speaker, a gong and a register, disposed in series in the circuit in the same arrangement as above described and as shown on the drawing. From the last engine house in the system a wire 7 leads back to the central station C, where it connects with one terminal of another normally closed relay switch S, which includes a movable blade 8 to which said wire 7 is connected. Another wire 9 connected to the other terminal of said switch and having a source of power 10 interposed therein

leads from the central station and forms the other incoming wire of the alarm circuit.

When an alarm is given by the opening of the main alarm circuit in the usual manner, the 5 various gongs and registers in all the engine houses as well as in the central station are actuated, and though the loud speakers are in the circuit, they do not interfere with the functioning of the alarm system. The latter thus functions in the normal manner.

The incoming telephone lines 11, by means of which fires are verbally reported to the central station operator, are of course connected to a receiving telephone T in said station. Wires 12 15 with a manual control switch 13 and condensers 14 therein are connected to the wires 11 and lead to an amplifier unit A of a standard type, there being a transformer 14a, in the line ahead of the amplifier. This amplifier unit is located 20 in the central station, power for which unit is provided by means of wires 15 connected to any suitable source of 110 v. A. C. current. It should here be noted that the capacity of the amplifying unit is sufficient to take care of as 25 many loud speakers as may be necessary for any particular installation, and, if required, a number of these units can of course be used to give the desired result.

Also connected to the amplifier unit is a microphone M located adjacent the telephone T so 30 as to be convenient to the operator answering the telephone. The switch 13 is also located convenient to said operator. A loud speaker 16, connected to the amplifier, is mounted in a convenient position in the central station, a hand switch 16a being interposed in the speaker line. It will thus be seen that when a telephone alarm 35 is received and answered by the operator he may cause the message, as received, to be amplified and broadcast generally into the central station, by closing the switches 13 and 16a.

At the same time he may, if it appears necessary, cause the conversation to be simultaneously broadcast from the speakers 4 in the various engine houses by means of the following circuit arrangement. Connected to the amplifier unit is an auto transformer 17 one wire 18 from which leads to a normally open terminal of the switch S. The other wire 19 from the transformer 17 leads to a normally open terminal of the switch S'. When the relays of these switches are actuated, the blades 2 and 8 respectively are moved to break the circuits to the wires 1 and 9 and close the same to the wires 55 18 and 19. The circuit wires 3 and 7 of the engine house circuit and in which the engine house loud speakers 4 are interposed as previously described, are thus connected in circuit with the amplifier unit. Sound waves passing 60 through the circuit from the telephone wires are thus amplified and broadcast into the engine houses, as well as in the central station, so that the listeners in the engine houses will instantly hear the telephonic alarm as it is being given 65 and can act accordingly. Also, if necessary, in connection with this operation of the loud speaker system, the central station operator may talk into the microphone and thus transmit instructions or other information to the men in 70 the various engine houses.

The current then flowing through the line and actuating the loud speakers is much weaker than that used and necessary in actuating the gongs and registers, and if the latter were left in the 75 circuit at that time, they would absorb so much

of this relatively weak current that the speakers would be rendered practically inaudible. For this reason the various auxiliary by-pass condensers 5 are employed. The condensers 5 are necessary however since when the main normal or alarm circuit is closed, the necessary current must then flow through the gong and register coils to hold the same.

Actuation of the various relay switches (which are arranged in a compact unit and are of a standard character which may be purchased on the open market) is preferably accompanied with the aid of a spring opened foot switch 20 interposed in the relay circuit wires 21, said switch being convenient to the foot of the operator seated at the desk upon which the telephone T is disposed. In this manner both hands of the operator are free for manipulating the telephone, writing down notes or other uses.

In order that the volume of sound emitted from the central station speaker 16 shall be modulated according to the load in the speaker circuit, the inductance 22 of the speaker mechanism is of an adjustable character, its adjustment being controlled by a relay 23 interposed in the circuit 21 of the other switch relays. Said inductance 22 is set so that when only the speaker 16 is operating, the resistance is relatively great so that the volume of sound emitted from the speaker 16 will not be unduly loud. When the load on the line is increased by the closing of the circuit to the engine house speakers, the resistance of the speaker 16 is automatically lessened so that the relatively small amount of current still available for the operation of said speaker 35 is sufficient to produce the desired volume of sound.

As previously explained, the operation of the register and gongs in the engine houses will be automatically discontinued when the loud speakers are broadcasting, so that they will not give forth any noises to distract the attention of the listeners from the verbal alarms being broadcast. It may here be noted that when the alarm circuit is opened by the closing of the speaker 45 circuit, the gongs and registers in the engine houses will be momentarily actuated. If no speech then comes from any speaker (as it should instantly) the crew in the corresponding engine house will know that their speaker is not functioning for some reason, and can report the fact 50 to the central station.

The operation of the register and gong in the central station however are not normally affected by the closing of the speaker circuit, and in order to temporarily cut them out to eliminate 55 the noise we provide the following arrangement:

A wire 24 is connected to the line 9 beyond the source of current 10 and leads to one terminal of a normally open relay switch 25, to the other terminal of which the wire 1 is connected. The wire 24 has a resistance 26 therein equal to that of the outside lines. The relay 27 of the switch 25 is connected to the circuit 21 of the other switch relays so as to be actuated 60 therewith upon the closing of the foot switch 20. When the relay switch 25 is closed therefore a short circuit between the wires 1 and 9 is established, in which the resistance is so great 65 that the adjacent gong G and register R will 70 not be actuated.

In connection with the operation of the amplifier, through the tubes of which current is always flowing to keep them warm, it is not desirable that the B current shall flow through these tubes 75

unless the speaker circuit itself is closed. The B circuit is therefore normally broken and the wires 28 of said circuit lead to a normally open switch 29 closed by the actuation of relay 27. 5 In order to enable the speaker 16 to be tested without closing switch 29, a hand test switch 30 is disposed to close the B circuit.

From the foregoing description it will be readily seen that we have produced such a device as 10 substantially fulfills the objects of the invention as set forth herein.

While this specification sets forth in detail the present and preferred construction of the device, still in practice such deviations from such detail 15 may be resorted to as do not form a departure from the spirit of the invention, as defined by the appended claims.

Having thus described our invention, what we claim as new and useful and desire to secure by 20 Letters Patent is:

1. In a fire fighting system which includes a central station and an engine house separate from said station, and an alarm circuit leading into the central station and thence to the engine 15 house, alarm producing mechanism interposed in the circuit within the engine house, a loud speaker interposed in the circuit within the engine house, a sound amplifying unit in the central station, a telephone line from the outside connected to the amplifier, circuit wires leading from the amplifier, and means operable selectively from within the central station to connect said wires to the alarm circuit wires leading to the engine house.

35 2. A system as in claim 1, with a loud speaker disposed in the central station and directly connected to the amplifier.

3. In a fire fighting system which includes a central station, an engine house separate from said station, an alarm circuit leading into the central station and thence to the engine house and an audible alarm in said circuit within the engine house; a normally closed switch in the circuit in the central station, a loud speaker interposed in the circuit within the engine house, a sound amplifying unit in the central station, a telephone line from the outside connected to the amplifier, circuit wires leading from the amplifier, and means to simultaneously open said switch and connect the wires to the alarm circuit between the switch and engine house.

40 4. A system as in claim 3, with means functioning automatically to prevent actuation of the audible alarm when said wires are connected to the alarm circuit.

55 5. A system as in claim 3 with a wire connected to the alarm circuit across the alarm therein, and a condenser in said wire.

6. In a fire fighting system which includes a central station, an engine house separate from said station, an alarm circuit leading into the central station and thence to the engine house and an audible alarm in said circuit within the engine house and another such alarm in the circuit within the central station; a loud speaker interposed in the circuit within the engine house, a sound amplifying unit in the central station, a telephone line from the outside connected to the amplifier, circuit wires leading from the amplifier, a selectively operated switch to connect the said wires to the alarm circuit, and means to simultaneously prevent the central station alarm from functioning.

7. A verbal fire alarm system for use in connection with a plurality of separated engine

houses and a central station, comprising an alarm circuit extending from the central station to all the engine houses, alarm producing mechanism interposed in the circuit within the engine house, loud speakers interposed in the circuit within all the houses, a sound amplifying unit in the central station, a telephone line from the outside separate from the alarm circuit and connected to the amplifier, and means operable at will from within the central station to selectively connect the amplifier to the alarm circuit.

8. In a fire alarm system which includes a central station, an engine house separate from said station and a two-wire alarm circuit leading into the central station and thence to the engine 15 house, each wire having a gap therein and a movable switch blade across the gap and connected to the wire on the engine house side of the gap and normally releasably engaging the wire on the other side of the gap to close the 20 circuit, a loud speaker in the circuit within the engine house, a telephone line from the outside, a sound amplifying unit connected to the line, a pair of circuit wires leading from the amplifier and terminating adjacent and normally spaced 25 from the switch blades to be engaged thereby when said blades move away from the alarm circuit wires, and selectively operable means to thus move the blades.

9. In combination with a fire alarm system, including an alarm circuit leading to an engine house, an alarm producing mechanism interposed in the alarm circuit within the engine house; a separate telephone circuit, and a loud speaker interposed in the alarm circuit within the engine 35 house, the alarm circuit and telephone circuit being arranged in operative connection.

10. In combination with a fire alarm system, including an alarm circuit leading to an engine house, an alarm producing mechanism interposed 40 in the alarm circuit within the engine house; a separate telephone circuit, a loud speaker interposed in the alarm circuit within the engine house, and switch means to selectively connect the telephone circuit with the alarm circuit.

45 11. A combination as in claim 10, including means to disconnect the alarm circuit, said switch means being arranged to connect the telephone circuit with that side of the alarm circuit when disconnected which includes the loud speaker 50 within the engine house.

12. In combination with a fire alarm system, including an alarm circuit leading to an engine house, and alarm producing mechanism interposed in the alarm circuit within the engine 55 house; a loud speaker interposed in the alarm circuit within the engine, a separate telephone circuit, a sound amplifying unit connected with said telephone circuit, and means to selectively connect said sound amplifying unit with the alarm circuit.

13. A system as in claim 12, in which said amplifying unit is disposed in a central station; there being a loud speaker in said station and directly connected to said amplifying unit.

14. A system as in claim 12, in which said amplifying unit is disposed in a central station; there being a microphone in said central station directly connected to said amplifying unit.

15. In combination with a fire alarm system, including an engine house, a central station, and an alarm circuit extending between the engine house and central station, said alarm circuit including alarm producing mechanism interposed 70 75

therein and disposed within the engine house; a separate telephone circuit leading to the central station from the outside, a loud speaker interposed in the alarm circuit within the engine house, and switch means in the central station arranged to selectively connect the telephone circuit with the alarm circuit.

16. A combination as in claim 15, including means in the central station to disconnect the alarm circuit; said switch means being arranged to connect the telephone circuit at a point on the

engine house side of said alarm circuit when so disconnected.

17. A system as in claim 1, with a loud speaker disposed in the central station and directly connected with the amplifier; and including means to automatically modulate the volume of sound from the central station loud speaker when said amplifier circuit wires are connected with the alarm circuit wires. 5
